US0D1064275S

(12) **United States Design Patent** (10) **Patent No.:** **US D1,064,275 S**
(45) **Date of Patent:** **** Feb. 25, 2025**

(54) **DENTAL SENSOR**

(71) **Applicant:** **BAE Systems Imaging Solutions Inc.**,
San Jose, CA (US)

(72) **Inventors:** **Bruce E. Willy**, Watsonville, CA (US);
Christopher E. Kohl, Austin, TX (US);
Mark K. Pierce, San Jose, CA (US);
Henry Silveira, Jr., Milpitas, CA (US);
Marc K. Thacher, San Diego, CA (US);
Deborah Ann True-Mobley,
Henderson, NV (US); **Muk-Wai Lui**,
Los Gatos, CA (US)

(73) **Assignee:** **Fairchild Imaging, Inc.**, San Jose, CA (US)

(**) **Term:** **15 Years**

(21) **Appl. No.:** **29/812,082**

(22) **Filed:** **Oct. 19, 2021**

(51) **LOC (15) Cl.** **24-01**

(52) **U.S. Cl.**

USPC **D24/158**; D24/176; D24/187

(57) **CLAIM**

The ornamental design for the dental sensor as shown and described.

DESCRIPTION

FIG. 1 is a front-left perspective view of the dental sensor. FIG. 2 is a top view of the dental sensor.

FIG. 3 is a rear-left perspective view of the dental sensor.

FIG. 4 is a front-left side view of the dental sensor; and,

FIG. 5 is a left side view of the dental sensor.

The broken lines showing the environment of the design are for illustrative purposes only and do not form part of the claimed design. The broken lines which form the boundaries of the design also do not form part of the claimed design.

1 Claim, 5 Drawing Sheets
